CREASED SHEET METAL PANEL AND THE
METHOD OF FORMING AND APPLYING
SUCH PANELS TO FRAME STRUCTURES

Leland A. Daines, Edmonds, Wash.

Application March 21, 1950, Serial No. 150,868

3 Claims. (Cl. 296—28)

1

My invention relates to sheet metal panels; and, more particularly, to creased sheet metal panels and the method of forming and applying such panels to frame structures.

The article and method are improvements in surfacing structures with sheet metal panels in such a way that the panel presents a uniform outward surface appearance at all times, as distinguished from sheet metal panels in prior use, which have their outward surface quite apparently distorted by changes in temperature, racking of the frame, and the like. The method of maintaining the uniform outward surface, briefly, comprises bowing a sheet metal covering panel by creasing the same along a plurality of parallel spaced-apart lines between opposite edges thereof, applying said bowed panel to a frame structure so that the convexly arcuate face is against said frame, and securing the panel to the frame so that the creases are partially flattened and the spaces between the creases are caused to assume outwardly bowed slightly convex curvatures. On expansion or contraction of the panel due to changes in temperatures, expansion and contraction is localized between the creases and dissipated in slight inward or outward movement of the convex curvatures.

Many structures are covered by panels of sheet metal. A common example is the covering of closed truck bodies. Where plain panels are used, these bodies often present a somewhat unsightly appearance due to apparent bowing in such sheet metal coverings, causing light to be reflected unevenly. The impression given is that the frame structure of the body is distorted or that the metal covering is not well secured to the frame. The distortion is usually not due to unevenness of the frame structure, which is often most solidly built, and is not due to lack of securing means for the panel, as many means are employed to afford ample anchoring of the panel to the frame. The uneven appearance is caused by expansion and contraction of the sheet metal due to changes in surrounding air temperatures. The apparent bowing of the panel between the points of securing is difficult to prevent. The frame studding and stringers form the principal points to which the sheet metal may be secured. Between these points of securing to the frame occurs the bowing that causes the uneven reflection of light.

The visible effect of panel bowing can be minimized by using an irregular panel, such as corrugated galvanized iron but distortion is still apparent.

2

Especially in metallic structures, such as bodies of vehicles, considerable noise is caused by the movement of the sheet metal structure against the frame at points which are not secured. Unpleasant rumbling and rattling noises may be caused by the action of wind on unsecured portions of a sheet metal covering, and these may also occur on non-movable structures.

The objects of my invention include: devising a method of applying sheet metal panels to structures so that a uniform outward surface appearance is presented throughout changes in temperatures; forming a sheet metal panel of such design that distortion due to expansion and contraction of the metal during temperature changes is so distributed and localized that no apparent bowing of the panel occurs; constructing a sheet metal covering in a form so that the covering will be bowed and, when secured to a structure with the convex face inward, said face will be compressed against the structure and there will be resistance to relative movement between the covering and the structure whereby noise due to such relative movement will be avoided; and providing in a sheet metal panel of economical design and sturdy construction having a long life, a shape whereby the panel presents a uniform outward surface.

The method, in brief, whereby the foregoing objects are met is as follows: I prefer to form my creased sheet metal panels of aluminum or aluminum alloys but other sheet metal material may be substituted. A plurality of parallel, spaced-apart creases, between opposite edges thereof and parallel to the other edges, is formed in the sheet metal with the crests of said crease on a common face of the panel whereby the opposite face thereof is bowed concavely.

One edge of the panel is attached to the frame structure to be covered, with the crests toward the frame. Then the rest of the panel is pressed to the structure so that the creases abutting the frame are partially flattened and the spaces between the creases on the outward face are caused to assume slightly outwardly bowed surfaces. The outward surface of said spaces is placed under tension and the inner surface is placed under compression.

Upon expansion or contraction of the panel, upon changes in temperature, the spaces between the creases may bow in or out but the bowing is generally uniform in each space and no noticeable change occurs. The uniformity of the surface is in marked contrast to the apparent distortion of the usual sheet metal panels.

The intermediate creases in the panel may be creased more sharply than the marginal creases, in which case the bow of the sheet is more parabolic than uniform. When the sheet is pressed against the frame, there is more pressure in the center of the sheet than near the edges, which is a desirable feature in that the center usually suffers the most distortion in the usual sheet metal panel.

Each crest of the creases being pressed against the frame structure, resistance against relative movement between the panel and the structure eliminates noise usually made by such movement, which is important, especially in coverings for vehicles.

My invention will be understood best from the following description, when read in connection with the accompanying drawings, in which:

Figure 1 is a perspective view of a truck and of a truck body covered by a form of my creased sheet metal panels;

Figure 2 is an elevational view, partly in section, of a vehicle body on which are secured said panels; and

Figure 3 is a fragmentary elevational view, enlarged and partly in section, of a skeleton frame structure covered by said panels.

Referring to Figure 1, there is depicted a truck 10, having a closed body 12 which is covered by creased sheet metal panels, the panels running horizontally on the sides. Horizontal panels are preferred because of the attractive appearance presented by the multiple horizontal lines and because when the horizontal panels are overlapped, one over another, rain will not enter between the panels and inside body 12, even in the absence of sealing materials. Creased panels may also cover the top of body 12.

In Figure 2 is shown in more detail the covering of a truck body. The skeleton frame structure of the truck body includes stringers 14, bed 16 positioned on said stringers, guards 18 on the edges of the bed, uprights 20 and joist 22. Covering the skeleton frame structure are creased sheet metal panels 24.

The panels may be made of various metals but it is preferred that they be light weight and have resilient qualities as well as good ability to stand exposure to weather without excessive deterioration.

Several factors enter into the decision as to the spacing of the creases in the panel. It may be desirable to have the creases spaced a certain distance because of aesthetic considerations or to have evenly spaced creases on a surface of a predetermined width. In general, the fewer creases the less the cost of forming the panel. Distortion of the panel in a direction perpendicular to its surface is uniform in each space between creases, as will be more fully developed later, due to the fact that the crest of each crease is pressed against the skeleton frame structure as the panel, originally of bowed shape, is secured to a flat framework. Therefore, it is necessary to have the creases close enough together to maintain the phenomenon of even distribution of distortion.

The details of the panel and the method of securing the same is most clearly depicted in Figure 3. Fragments of the skeleton frame of a truck body shown include bed 26, guard 28 on the edge of the bed, upright 30, bracket 32, joist 34 and corner piece 36. Portions of three panels 38 are shown. Each panel has formed therein, as by pressing, a plurality of parallel, longitudi-

nally-extending, spaced-apart creases 40, with the crests 42 all disposed on a common face of the sheet metal wall covering panel 38.

Before the panels are secured to the frame, they are longitudinally bowed with the crests disposed on a convexly arcuate face, as at 44 in Figure 2. When the panels are secured to a frame structure the crests are positioned abutting the outer surface of the frame to be covered and are somewhat flattened. Crests 42 press against the frame with considerable force, which explains the absence of the noise usually incident to the covering of a vehicle body by metal panels due to the striking of the panels against the frame as the truck body sways and bumps. Drivers of vehicles covered by my new creased panels have remarked on the absence of the noise incident to the use of the usual plain metal covering for vehicles.

The space 46 between creases 40 is outwardly bowed with a convex curvature, the outer surface 48 being under tension and the inner face 50 being under compression.

One of the main features of my invention is the localization of distortion of the panels 38, due to temperature changes, whereby outer surface 48 in each space 46 between creases 40, moves inwardly or outwardly a uniform distance. Uneven distortion of the usual metal panel during temperature changes, causes unsightly appearance as light reflects unevenly from the panel. In the present panel, little tendency is present to concentrate the distortion in one area as all areas are under pressure and have about the same resistance to distortion. Each space 46 between creases moves inwardly or outwardly, when there is a temperature change, about the same distance, and, the distance being small, the distortion is not apparent.

The marginal creases do not need to be formed as sharply as the intermediate creases as the securing means near the margin assist the marginal portion in resisting distortion. Therefore, it may be preferred to have intermediate creases formed more sharply than marginal creases, in which case an unsecured panel is longitudinally bowed more parabolic than uniform, as is shown at 44 in Figure 2. More pressure is placed on the crests of the intermediate creases as they abut the frame structure to which they are secured, and there is more resistance to relative movement between said crests and said structure, at these points farthest from the marginal edge where the panel is secured, and the crests and structure move as one piece whereby no noise is created as the vehicle moves.

One means of securing the creased sheet metal panels to a structure is illustrated in Figure 3. Panels 38 are lapped and screws 52 run through the lapped joint, there being washers 54 on the screws. At the upper corners of the truck body is a transversely curved member 56, lapped at its upper edge by one panel and lapping at its lower edge the panel on the side-wall. The lowest panel is lapped over the upper end of guard 28 at 58.

Method of applying the sheet metal panels

In Figure 2 is shown a single panel covering the sidewalls of a vehicle body skeleton structure. The drawing shows a sidewall panel, at 44, partially secured to the frame structure. Taking a sheet metal panel, creased along a plurality of parallel spaced-apart lines extending between opposite edges thereof and parallel to the other

edges, one edge is secured to the frame skeleton. The convexly arcuate face with the crests of the creases is directed toward the structure. Then the panel is unbowed by pressing the same to the frame structure so that the crests abut the frame structure and the creases are partially flattened, and the spaces between the creases on that face directed away from the frame structure are caused to assume outwardly bowed slightly convex curvatures. The panel is secured to the frame structure in this position.

Upon the occurrence of expansion or contraction of the sheet material, the forces thereof are localized between the creases and dissipated in outward or inward movement of the outwardly bowed slightly convex portions of the sheet metal panels.

Reflection from the outer surface of the creased panel is then substantially uniform throughout all changes in temperature. The crests of the creases in the panel tightly abut the frame structure so there is little possibility of relative movement therebetween and no noise is created by one moving against the other during movement of the vehicle.

It is preferable, especially when wide panels are being used, to form the intermediate creases more sharply than the marginal creases, whereby the bow is more parabolic than uniform, and, when the sheet is pressed to the frame structure, there is increased pressure at the intermediate ridges over the pressures pertaining with the marginal ridges, whereby it is insured that the central, unsecured portion will tightly abut the frame structure.

Various modifications of the specific embodiment shown and described will be apparent to those skilled in the art, without departing from the spirit of the invention, and I do not wish to be understood as limiting myself to said specific embodiment.

Having thus described my invention, I claim:

1. In the application of sheet metal panels to frame structures, the method, comprising: bowing a sheet metal panel so that one face is convexly arcuate by creasing the same along a series of parallel, equidistantly spaced-apart lines extending between opposite ends thereof and parallel to the sides thereof with the crests of the creases all disposed on a common face of the panel, applying said bowed panel to a frame structure so that the convexly arcuate face is directed

toward the frame structure, securing one of the side edges alongside the creases to said frame structure from end to end, then unbowing said panel by pressing the same to said frame structure so that the creases abut the frame structure and are partially flattened and the spaces between the creases on that face directed away from the frame structure are caused to assume outwardly bowed slightly convex curvatures, and securing said sheet to the frame structure in said unbowed relationship, whereby upon the occurrence of expansion or contraction of the sheet material the forces thereof are localized between the creases and dissipated in outward or inward movement of the outwardly bowed slightly convex portions of the sheet metal panels therebetween.

2. In the method of claim 1 in which, in the bowing of the sheet metal panel by creasing the same, the intermediate creases are formed more sharply than the marginal creases of said plurality whereby the bow is more parabolic than uniform and, when the sheet is pressed to the frame structure there is increased pressure at the intermediate ridges over the pressures pertaining with the marginal ridges.

3. A vehicle body, comprising: a skeleton frame structure, and a sheet metal covering panel on said frame structure, said panel being characterized by having a series of like creases extending between opposite edges of the panel, the crests of said creases being on the inner face of said panel and being tightly pressed against said frame structure by internal strain in said panel, the panel between said creases being outwardly bowed and the outer faces of said outwardly bowed portions between said creases being under tension and the opposite inner faces thereof being under compression.
